Fig.1

Fig.2

Fig.3

Fig.5

Fig.4

Fig.6

FIG. 1 is a side elevational view of the hand operated sprayer showing my new design.

FIG. 2 is a front elevational view thereof,

FIG. 3 is a top plan view thereof,

FIG. 4 is a bottom plan view thereof,

FIG. 5 is a rear elevational view thereof, and

FIG. 6 is a perspective view of the sprayer.

The side not shown is substantially the same in appearance as that shown in FIG. 1. The pump tube is broken away in the various figures to show indefinite length.

The essential features of the design are as shown in solid lines.

I claim:

The ornamental design for the hand operated sprayer, as shown and described.
